UNITED STATES PATENT OFFICE.

MARTIN HEMLEB, OF ELIZABETH, NEW JERSEY, ASSIGNOR TO THE SINGER MANUFACTURING COMPANY, A CORPORATION OF NEW JERSEY.

MOTOR CONTROLLER.

Application filed October 25, 1919. Serial No. 333,346.

To all whom it may concern:

Be it known that I, MARTIN HEMLEB, a citizen of the United States, residing at Elizabeth, in the county of Union and State 5 of New Jersey, have invented certain new and useful Improvements in Motor Controllers, of which the following is a specification, reference being had therein to the accompanying drawings.

10 This invention relates to speed-controllers for small motors of the type commonly used for driving sewing machines and the like. It has for an object to provide a controller of the foot-operated type which is adapted 15 to be operated either on the floor in connection with a portable sewing machine or on the usual treadle-plate of a sewing machine stand or cabinet.

10 This invention relates to speed-controllers for small motors of the type commonly used for driving sewing machines and the like. It has for an object to provide a controller of the foot-operated type which is adapted 15 to be operated either on the floor in connection with a portable sewing machine or on the usual treadle-plate of a sewing machine stand or cabinet.

A further object of the invention is to 20 provide a foot-operated motor-speed-controller of compact, simplified and sturdy construction which is unlikely to get out of order and the parts of which are readily accessible for replacement or repair. Further 25 objects of the invention will appear from the following description and claims.

In its preferred embodiment, the controller comprises a casing element and a base or supporting element with means for detachably securing them together. The casing element forms a housing for a circuit controlling element or rheostat which is detachably mounted as a unit within said casing and includes a contactor which is operated by means of a pedal sustained by the casing and located at a level between the top and bottom of the latter thereby insuring compactness. The pedal, which is preferably made up in the form of a lever, is 40 pivotally mounted at one end of the casing and at its free end is extended laterally to form a foot-piece located in front of the casing at one side of the latter and over an extension of the base which prevents tilting 45 of the entire device during depression of the pedal.

In a sewing machine stand or cabinet, the usual treadle-plate and cabinet supporting legs fill up the space within convenient reach 50 of the operator's foot and when such a cabinet is equipped with a motor driving attachment including a portable foot-controller of the type heretofore used, such controller must be placed at one side of the cabinet necessitating the assumption of an awkward 55

and unnatural position by the operator in order that the controller may be reached by the foot.

One form of construction of the present device possesses a feature of importance in 60 that fastening means are provided for securing the casing to the base so constructed as to permit the casing to be readily removed from the base and mounted without the use of additional fastening devices upon the usual treadle-plate of a sewing machine cabinet where it is within easy reach of the operator's foot. The controller is thus particularly adapted for use with motor-driven 65 sewing machines of either the portable or 70 cabinet type. It is to be understood, however, that the feature of ready detachability of the casing and base is not essential to the invention in its broader aspects.

In the accompanying drawings, Fig. 1 is 75 a side elevation of the controller with the side wall of the casing element removed. Fig. 2 is a horizontal section through the casing. Fig. 3 is a disassembled perspective view of the controller. Fig. 4 is a side 80 elevation of the controller as mounted on the usual treadle-plate of a sewing machine cabinet. Fig. 5 is a bottom plan view of the parts shown in Fig. 4 and Fig. 6 is a section on the line 6—6, Fig. 5. 85

In the particular embodiment of the invention chosen for the purpose of the present disclosure, the controller comprises a base 1 having an elongated substantially 90 rectangular body-portion from which extends the arm 2 at an angle to the body-portion. This base preferably has a substantially flat upper surface 3 and has secured thereto the flat bottom wall 4 of the controller casing 5 including the flat side 95 walls 6 and 6', the former being removably secured to the main body-portion of the casing by two screws 7 and being detachable without the necessity of separating the casing from the base. 100

The means for locating and fixing the casing 5 upon the base 1 preferably comprises the screw 8 which enters the hole 9 in the extension or ear 10 and passes through the hole 11 in the base 1; the lower end of the screw 8 being threaded into the special nut 12 from the upper surface of which projects the steady pin adapted to enter the alined apertures 14, 15 in the base 1 and ear 10, respectively. The nut 12 is in the form 110

of a disk which is cut away to form the curved surfaces 16, 16 shaped to grip the ribs of the usual treadle-plate, as will be hereinafter explained. The casing 5 is also 5 formed with a downwardly projecting stud- 70 pin 17 which enters the aperture 18 in the base 1.

Detachably mounted as a unit within the 10 casing 5 is the circuit controlling element α , preferably in the form of the usual rheostat including a porcelain base 19 carrying the usual resistance coils terminating in the contact-points 20. A contactor-arm 21 is pivoted on the post 22 fixed to the base 19 15 and carries the contact spring 23 adapted to play over the contact-points 20. The coil spring 24 surrounding the enlarged base of the post 22 serves to yieldingly elevate the arm 21 and shift the contact spring to "off" 20 position.

The arm 21 is formed in its forward face with a longitudinal slot 25 which is entered by the lateral pin 26 projecting inwardly from the inner face of the pedal-lever 27 at 25 a point intermediate the ends of said pedal-lever. Secured to one end of the lever 27 is the lateral fulcrum pin 28 which enters the apertured lug 29 formed on the casing 5. The outer face of the lever 27 is substantially 30 flush with the seat for the cover-plate 6; the front wall 30 of the casing being cut away to provide stops 31 limiting the vertical movement of the pedal-lever. A coil spring 32, surrounding the fulcrum-pin 28 35 and anchored at its opposite ends to the casing 5 of the lever 27, respectively, serves to yieldingly elevate the lever 27 and assist in elevating the arm 21. The lever 27 is provided with an extension 33 at its free end 40 which is disposed in a horizontal position over the arm 2, as shown in Fig. 2. It will be noted that the pedal 33 is located at a level between the top and bottom of the casing 5, and at one side of the space between 45 the planes of the walls 6, 6', giving a compact construction and one which is easily manipulated by the operator who may rest the heel upon the floor with the foot alongside the casing 5 and easily press the ball 50 of the foot upon the extension-piece 33. The positioning of the lever 27 alongside the controller element 19 whereby the operative connection between the controller element and said lever may be made intermediate the 55 ends of the latter are constructive features of importance in that they afford a very compact and sturdy device which is easy to carry around with a portable sewing machine outfit and which will withstand the 60 wear and tear of long continued or harsh usage.

The controller as assembled in Figs. 1 and 2 is particularly adapted for use in connection with the usual portable motor-driven 65 sewing machines such as are commonly pro-

vided with suitable hand cases for transportation. The controller, because of its compact construction and, particularly, because of its low height and light weight, is adapted to be placed under the bracket-arm of a portable sewing machine outfit and thus housed within the usual hand-carrying case. If, however, it is desired to apply the controller to a sewing machine of the cabinet type, the usual sewing machine treadle-plate 70 t affords a convenient support which may be taken advantage of by so spacing the fastening devices such as the stud 17 and screw 18 that when the stud 17 is located between and in contact with the adjacent 75 ribs 34 of the treadle-plate, the curved surfaces 16 of the nut 12 are in position to tightly grip the similar ribs 35. The rear end of the controller preferably fits against the usual heel rest 36 of the treadle-plate. The surfaces 16 of the nut 12 may, if desired, be roughened to cause them to more securely bite into and grip the ribs 35 of the treadle-plate. Suitable rubber feet 37 are preferably provided for the base-plate 1. The 80 control-wires from the motor lead into the casing 5 through the insulating bushing 38. The term base used herein is not necessarily intended to distinguish the element 1 from the treadle-plate t , as the latter also constitutes a base for the casing 5 when the controller is installed in a sewing machine stand. Both of the plates 1 and t are apertured for reception of the steadyng means 8 and 17. It will be noted that the cover-plate 6 may be readily removed without disturbing the assembled relation of the casing and base, whether the base is considered as the plate 1 or treadle-plate t . 90

Having thus set forth the nature of the invention, what I claim herein is:—

1. In a motor speed controller, in combination, a base, a casing, a pedal-operated circuit controlling unit housed within said casing and means for detachably securing said casing to said base, said means being adapted for use in securing the casing to the treadle-plate of a sewing machine. 105

2. In a motor speed controller, in combination, a base, a casing having a substantially flat bottom surface, a pedal-operated circuit controlling unit housed within said casing, and means for detachably securing said casing to said base, said means being adapted for use in securing the casing upon the upper surface of the treadle-plate of a sewing machine. 110

3. In a motor speed controller, in combination, a casing, a base adapted to rest upon the floor and carrying said casing, a circuit controlling unit including a shiftable contactor housed within said casing, a pedal lever movable toward and away from said base and pivoted at one end to said casing independently of said circuit controlling 115 120 125

unit, and an operative connection between said pedal and said shiftable contactor, said pedal lever being disposed below the level of the top of said casing.

5. 4. In a motor speed controller, in combination, a base, a casing, means including spaced elements for locating and fixing said casing on said base, a circuit controlling element housed within said casing, and a 10 pedal sustained by said casing and operatively connected to said circuit controlling element, said spaced elements being so shaped and located as to adapt the casing to be secured to the usual treadle-plate of a 15 sewing machine.

5. In a motor speed controller, in combination, a base, a casing including a removable side cover-plate, means for detachably securing said casing to said base permitting 20 removal of the cover-plate without disturbance of said means, a circuit controlling element housed within said casing, and a 25 compressible pedal for operating said controlling element, said pedal being mounted within said casing and including an angular 30 extension constituting a foot piece accessible exteriorly of said casing.

6. In a motor speed controller, in combination, a base having a main body portion 35 and an extension, a casing of substantially rectangular cross section mounted on the main body portion of said base, the distance between the side walls of the casing being less than the distance between its end walls, 40 a circuit controlling element housed within said casing, and operating means sustained by said casing and including an arm having a laterally extending foot-piece, disposed substantially over said extension of the base and at one side of the space between the 45 planes of the said side walls of the casing.

7. A controller comprising a supporting base element, a casing element on the base element, a circuit controlling unit mounted within said casing element and including a plurality of resistor-connected contact points

disposed in a substantially vertical plane and a contact lever-arm pivotally mounted on a substantially horizontal axis for movement over said contact points, a pedal lever- 50 arm pivotally connected to one of said elements for movement about a horizontal axis and extended to one side of the casing element below the top of the latter, and a stud rigid with one of said lever-arms and sus- 55 tained substantially at the elevation of the other of said lever-arms and connected to the latter.

8. A motor controller having a casing and base adapted to rest upon the floor and having an extension laterally of said casing, a circuit controlling element housed within said casing, an L-shaped lever having one of its arms pivoted to said casing, the other arm of said lever constituting a foot-piece 60 extending laterally of the plane of the lever proper and disposed over said extension of the base, and an operative connection between said lever and circuit controlling 65 element. 70

9. A motor controller comprising a casing of substantially rectangular horizontal cross-section with its side walls spaced apart a lesser distance than its end walls, said casing having a base adapting it to rest upon the 75 floor with its said side walls in substantially vertical planes, said base having an extension laterally of the space between the planes of said side-walls, a circuit controlling element mounted within said casing, an operating 80 lever connected to said element and mounted mainly within said casing, said lever having an extension projecting exteriorly of said casing and affording a foot-piece, said foot-piece being disposed mainly at one side of 85 the space between the planes of said side walls of the casing and over said extension of the base.

In testimony whereof, I have signed my name to this specification.

MARTIN HEMLEB.
